CARL GUSTAF OTTO HJALMAR VON KÖHLER, OF STOCKHOLM, SWEDEN.

TIME-ALARM FOR ELECTRIC LOGS.

SPECIFICATION forming part of Letters Patent No. 772,522, dated October 18, 1904.

Application filed June 23, 1903. Serial No. 162,808. (No model.)

To all whom it may concern:

Be it known that I, CARL GUSTAF OTTO HJALMAR VON KÖHLER, engineer, a resident of 16 Sturegatan, Stockholm, in the Kingdom of Sweden, do hereby declare the nature of my invention for Improvements in Time-Alarms for Electric Logs, and in what manner the same is to be performed, to be particularly described and ascertained in and by the following statement.

Electric-log recording apparatus in which an electric current is closed by the log for each passed unit of the distance, hereby turning a lever that produces a mark in a paper strip continuously brought into motion by a clock-work, are already known. Such apparatus have the inconvenience that they cannot indicate if the motion of the log has been stopped under a longer or shorter time for any reason— for instance, on account of sea-grass having snared itself round the same. In such case the distance between the marks in the paper strip will be longer, so that the observer believes that the velocity of the vessel has been less than in the reality. In other words, the recording apparatus indicates wrong.

The present invention relates to an improvement in such log - recording apparatus, by means of which improvement in the above case a signal is given indicating that the log is not working normally.

In the accompanying drawings a part of my improved time-alarm for electric-log recording apparatus is illustrated in side view in Figure 1. Fig. 2 illustrates a part of it in perspective view.

a is the electromagnet, and *b* the lever operated by the same and connected to a shaft *n*, also carrying another lever, *t*, for producing the marks in the paper strip *p*. The lever *b* is provided with a pawl *c*, at the motion of the lever turning a ratchet-wheel *d*, which may be connected to a hand *g*, movable over a graduated plate *r*, provided with electric contacts. When the hand passes over these contacts, an electric current is closed and a signal is produced.

According to the present invention there is near the outer end of the double lever *b* placed a gear-wheel *e*, rotated by a clockwork and

meshing with a rack *f*, which is movable lengthwise in a guide *g*, but also oscillates vertically if operated upon by a lever *h*, which is pivoted on a stud and is located with one end between the rack and the rear end of the lever *b*. The rack *f* is connected to a spring *i*, forcing it backward, while the gear-wheel *e* pushes it forward during its rotation. As soon as the fore end of the lever *b*, which is located over the electromagnet *a*, is lowered by the latter under the regular rotation of the log the rear end of the lever *b* is raised, thereby turning the lever *h*, which in turn raises the fore end of the rack *f* from the gear-wheel *e*, whereupon the rack is drawn back by the spring *i*. When the current passing the electromagnet is again broken and the electromagnet lets the lever *b* loose, the rear end of the latter sinks down again into the position shown in the drawings, the rack *f* being then again caused to mesh with the gear-wheel and to be pushed forward by it until the lever *b* is turned again by the log and the rack is pushed backward by the spring *i*. If now the rotation of the log would cease, so that no current were closed in the electromagnet, the fore end of the lever *b* becomes not lowered. In consequence the lever *b* is not turned and the rack not raised out of its meshing with the gear-wheel *e*, but becomes successively pushed forward by the said wheel until the rack meets an electric contact *k*, located in its way, thereby closing a current to an electric signal device *s* and producing a signal indicating that the apparatus is not in order. Instead of the electric contact *k* a mechanical alarm apparatus may be employed.

The way that the rack ought to be pushed by the gear-wheel for the purpose of meeting the contact *k* may be made longer or shorter by placing behind the rear end of the rack a plate or the like *l*, that may be adjusted more or less far from the gear-wheel *e*. For this purpose the plate, for instance, may be curved and connected to a lever *m*, pivoting on the shaft of the gear-wheel *e*, so that the situation of the plate may be changed by turning the lever and the backward stroke of the rack limited, thus permitting changes in the length of the way of the rack to the contact *k*. This

is very advantageous if it is desired to obtain a signal when the vessel has not the velocity wished for. In such a case the plate *l* is adjusted so that the length of the way which the 5 rack *f* is already moved by the gear-wheel *e* before it is pushed back through the closing of the electric current will be less than the distance between the stop-plate *l* and the contact *k*. If the velocity of the vessel grows 10 less, the rack is pushed forward against the contact, and a signal is given before the log has closed the current, and thus before the rack has been drawn back by the spring *i*. The lever *m* may be provided with a pin *o*, 15 projecting over one end of the lever *h* in such a manner that by depression of the said lever *m* the lever *h* can be turned, thereby raising the rack *f* out of its meshing with the gear-wheel when desired.

20 The device above described may of course be employed even in other apparatus working in the same manner as the log-recording apparatus.

Having now particularly described and ascertained the nature of my said invention and in what manner the same is to be performed, I declare that what I claim is—

1. In a time-alarm for electric logs and the like, the combination of a gear-wheel, a clock-work for rotating same, a sliding rack meshing with the wheel and arranged to operate 30 an alarm when moved a given distance by the

wheel, a spring returning the rack to normal position, an oscillating lever under the rack, an electromagnet adapted to oscillate the said 35 lever and arranged in a circuit intermittently closed by the movable part of the apparatus, a pivoted lever, the one end of which is located between the rack and the end of the oscillating lever and an adjustable stop for the 40 backward movement of the rack, substantially as described.

2. In a time-alarm for electric logs and the like, the combination of a gear-wheel, a clock-work for rotating same, a sliding rack meshing with the wheel and arranged to operate 45 an alarm when moved a given distance by the wheel, a spring returning the rack to normal position, an oscillating lever under the rack, an electromagnet adapted to oscillate the said 50 lever and arranged in a circuit intermittently closed by the movable part of the apparatus, a pivoted lever, the one end of which is located between the rack and the end of the oscillating lever and a stop on a lever pivoting on 55 the shaft of the gear-wheel, substantially as described.

In witness whereof I have hereunto set my hand in presence of two witnesses:

CARL GUSTAF OTTO HJALMAR VON KÖHLER.

Witnesses:

JOHN EDBERG,
H. TELANDER.
